UNITED STATES PATENT OFFICE

146,398

DESIGN FOR A SADDLE

Walter D. Allison, Montrose, Colo.

Application March 29, 1946, Serial No. 128,072

Term of patent 7 years

(Cl. D38—8)

To all whom it may concern:

Be it known that I, Walter D. Allison, a citizen of the United States, residing at Montrose, in the county of Montrose and State of Colorado, have invented a new, original, and ornamental Design for a Saddle, of which the following is a specification, reference being had to the accompanying drawing, forming part thereof.

The figure is a side elevational view of a saddle showing my new design, the opposite side thereof presenting substantially the same appearance as the side shown.

I claim:

The ornamental design for a saddle, as shown and described.

WALTER D. ALLISON.
